UNITED STATES PATENT OFFICE.

JULIUS SCHIRRA, OF PITTSBURG, PENNSYLVANIA, ASSIGNOR OF ONE-FOURTH TO EDMUND F. BARNHART, OF SAME PLACE.

RING FOR PROTECTING PROJECTILES.

SPECIFICATION forming part of Letters Patent No. 643,071, dated February 6, 1900.

Application filed June 30, 1899. Serial No. 722,406. (No model.)

To all whom it may concern:

Be it known that I, JULIUS SCHIRRA, a citizen of the United States, residing at Pittsburg, in the county of Allegheny and State of Pennsylvania, have invented or discovered a new and useful Improvement in Rings for Protecting Projectiles, of which the following is a full, clear, and exact description, reference being had to the accompanying drawings, forming part of this specification, in which—

Figure 1 is a view in side elevation of a shell provided with my improved protecting rings. Fig. 2 is a face view of one of the rings joined. Fig. 3 is a perspective view of a ring disconnected. Fig. 4 is an enlarged longitudinal sectional view taken through the joined ends. Fig. 5 is a perspective detail view of the connecting ends, showing the resilient cord wrapping. Fig. 6 is a cross-sectional view on the line VI VI of Fig. 5. Fig. 7 is a detail view in longitudinal section of a modified construction of joint. Fig. 8 is a detail view of the joint, showing means for adjustment in length.

My invention relates to devices for protecting projectiles or other cylindrical objects from injury or abrasion during transportation; and it consists of a ring adapted to be applied to the projectile A at both ends, entirely surrounding it, projecting outwardly beyond the rifling-ring a and forming in effect diametral projecting rollers upon which the projectile may be rolled across the floor or deck in a straight line.

Referring now to the drawings, 2 represents a metallic band, adapted to be bent around into circular form, so as to conform to the circumference of the projectile, the meeting terminals of the band being provided with any suitable means for joining them together, such as interfitting loops 3, through which may be passed a pin 4. The ring is provided with a protecting substance 5—such as fiber, leather, &c.—adapted to bear upon the projectile and capable of partial compression or resiliency, as desired. In the principal figures of the drawings I have shown this material in the form of an internal band, the endslapping at the joint in order to provide a solid bearing, while in Figs. 5, 6, and 7 I have shown the metallic band, or annulus 2 as being wrapped with cord or other similar mate-

rial 6, which is an efficient and economical construction.

In Fig. 7 the meeting ends of the ring 2 are shown provided with interfitting teeth 7, adapted to engage at the desired point of tension, one end of the ring being provided with a spring locking-plate 8, adapted to securely keep the ends in engagement when applied, the joint being readily disconnected upon raising the spring by the upturned end 9.

In Fig. 8 I have shown one of the terminals of the band 2 as being provided with a threaded extremity 10, upon which is screwed an adjustable eye 11, adapted to fit between the loops 3 of the other end and to be secured thereto by the pin 4, and by this construction I am enabled to very accurately adjust the rings to the circumference of the projectile, the eye 11 interfitting with pins 4 at each half-turn.

When protected by my improved protector, the rifling-ring of the projectile is safe from injury, and the projectile itself, as has been said, may be rolled with ease. The rings are easily and quickly removed, and the elasticity of the metal is sufficient to cause the ring to spring apart, as shown in Fig. 3, so that removal is facilitated, when, if desired, they may be applied to other projectiles and used again, as there is no wear or deterioration of their usefulness.

It will be understood that the metal band is not absolutely necessary and may be dispensed with, in which case the ring may be composed entirely of fiber or such other material as will provide sufficient adhesion and form a good protective covering.

What I claim is—

1. A protector for projectiles consisting of a continuous circular band of elastic material, a protecting covering thereon on the inner side, and interfitting ends adapted to be coupled together.
2. A protector for projectiles consisting of a continuous circular band of elastic material, interfitting ends adapted to be coupled together and a lining of protecting material on the inner side adapted to overlap at the joint of the ring.
3. A protector for projectiles consisting of a continuous circular metallic band formed into an annulus with interfitting ends having

648,071

loops adapted to be secured together by a pin, adapted to spring open by elasticity of the ring when released, and provided with a covering of protecting material adapted to make contact with the projectile.

5. A protector for projectiles consisting of a continuous circular metallic band formed into an annulus with interfitting ends adapted to be secured together adjustably and adapted to spring open by elasticity of the ring when

released, and provided with a covering of protecting material adapted to make contact with the projectile.

In testimony whereof I have hereunto set my hand.

JULIUS SCHIRRA.
